(57) **CLAIM**

The ornamental design for a display screen portion with icon, as shown and described.

DESCRIPTION

FIG. 1 is a front view of a display screen portion with icon showing my new design; and,

FIG. 2 is a front view of a display screen portion with icon of FIG. 1, in which a mobile terminal in broken lines is provided to illustrate an example environment.

The broken line drawing of the mobile terminal, and the numbers, symbols and otherwise images shown in broken lines in FIG. 2 are for illustrative purposes only and form no part of the claimed design.

1 Claim, 2 Drawing Sheets**FIG. 1**

FIG. 2
